UNITED STATES PATENT OFFICE.

WILLIAM G. ZIMMERMAN, OF HARRISBURG, PENNSYLVANIA.

JAR-LIFTER.

1,196,833.

Specification of Letters Patent.

Patented Sept. 5, 1916.

Application filed June 5, 1914. Serial No. 843,119.

To all whom it may concern:

Be it known that I, WILLIAM G. ZIMMERMAN, a citizen of the United States of America, residing at Harrisburg, in the county of Dauphin and State of Pennsylvania, have invented certain new and useful Improvements in Jar-Lifters, of which the following is a specification, reference being had therein to the accompanying drawing.

10 This invention relates to a jar lifter and has for its principal object the production of a simple and efficient device which is adapted to engage the neck of a jar for facilitating the lifting of the same without injury to a person's hands.

15 Another object of this invention is the production of a jar lifter which is formed from a blank strip of resilient wire which is folded at certain portions so as to provide 20 spring jaws for engaging the neck of a jar in such a manner as to allow the arms thereof to easily yield when undue pressure is brought to bear thereon thereby relieving the strain from the jaws so as to allow the 25 jaws to remain in engagement with the jar.

With these and other objects in view this 30 invention consists of certain novel combinations, constructions, and arrangements of parts as will be hereinafter fully described and claimed.

In the accompanying drawing:—Figure 1 is a detailed perspective view of the jar lifter illustrating the manner in which the device is used in lifting a jar. Fig. 2 is a 35 fragmentary side elevation of the jar lifter showing the same attached to or engaging the upper portion of a jar. Fig. 3 is a fragmentary sectional view through a portion of the jar lifter illustrating the manner in 40 which the same engages a jar and showing how the several portions will yield for supporting jars of extraordinary weight thereby relieving the strain from the jaw. Fig. 4 is a top plan view of the jaws showing the 45 arms in section. Fig. 5 is a plan view of a portion of the blank strand of wire from which the device is formed.

50 Referring to the accompanying drawing by numerals it will be seen that this jar lifter is formed from a single strand of resilient wire coiled to form a spring 1 from which extend the integral diverging arms 2 and 3. These arms 2 and 3 are bent inwardly at their lower ends as indicated at 55 to provide the projections 5 extending at right angles to the arms 2 and 3. These pro-

jections 5 are provided with the curved resilient fingers 6 extending therefrom at substantially right angles while the jaws 7 are formed integral and folded backwardly 60 upon the fingers 6 and terminate in the lips 8 folded backwardly to rest upon the rear surfaces of the jaws 7 so as to conform in contour thereto.

When this device is in use the spring 65 arms will normally hold the jaws and resilient fingers in spaced relation and at a distance sufficient to allow the passing of the neck of a jar 9 to be passed therebetween so as to allow the jaws to be positioned below 70 the annular rib 10 of the jar 9. The handles may then be compressed so as to bring the jaws 7 into engagement with the jar 9 whereby the jaws will rest under the annular rib 10. By lifting upwardly the jar may 75 be lifted to a desired position. It is particularly desirable to use this jar lifter for lifting heated jars such as is necessary when filling the jars with a heated liquid when the 80 contents within the jars has been cooked and it is desired to remove the jars to a desired position.

By referring particularly to Fig. 3 it will be noted that the action upon the jaws is relieved by the resilient fingers 6 when a 85 very large jar or a jar of extraordinary weight is being lifted. In using the device at such a time the jaws will be clamped under the annular rib 10' of the jar 9'. Since this lifter is formed to provide resilient fingers 6 formed integral upon the jaws 7 when the lifter is lifted or moved upwardly 90 so as to lift the jar, the weight of the jar will cause the resilient fingers 6 to yield slightly. The jaws however are formed integral upon these fingers 6 but will remain in engagement with the jar 9' and rest under the rib 10'. The springing or resilient action of the fingers 6, will cause the same to 95 yield so as to spring outwardly as disclosed in full lines in Fig. 3. This will prevent the jaws from being pulled from engagement with the rib 10' and will prevent the several portions from becoming broken as would be the case if the handles 2 and 3 were soldered 100 or otherwise fixedly secured directly to the jaws 7. As soon as the jar is removed and the weight is relieved from the jaws the resilient fingers 6 will again spring so as to 105 assume their normal correct position so as to allow the lifter to again engage a jar. It will of course be seen by referring to Fig. 3

that the springing action of the resilient fingers 6 when the same yield and spring outwardly and upwardly will cause the jaws 7 to more firmly engage the rib 10' of the jar 9' thereby positively retaining the jar 9' in engagement with the lifter.

Since this jar lifter is formed from a single strand of resilient wire, it can be constructed very cheaply and will not become broken, since there are not any separable parts. It should also be noted there is not any danger of dropping a jar, although the lifter is formed of a single strand of wire, since the fingers 6 extend in opposite directions or upon opposite sides of the vertical plane of the coiled spring. Therefore, the jaws 7 will be supported at opposite ends and in this manner a jar will be firmly supported by the jaws taking up the strain evenly. If the jaws were supported at the same ends in direct alinement with each other, the weight of a jar would cause the jaws to sag at their unsupported ends and this action would make the supporting or carrying of a jar very difficult. As the fingers and jaws are now formed, however, a jar will be held evenly without danger of falling.

From the foregoing description it will be seen that a simple and efficient jar lifter has been produced which is formed from a single

strand of resilient metal which is folded to provide springing jaws formed integral upon resilient fingers formed upon lifting handles whereby the jaws may engage a jar 35 and positively retain the jar in a position for being easily lifted when desired.

What I claim is:—

In a jar lifter of the class described, formed from a single strand of resilient 40 wire, the combination of a coiled spring, diverging arms extending from said spring, said arms terminating in inwardly extending projections, fingers extending from said projections in opposite directions so as to 45 be formed upon opposite sides of the vertical plane of said coiled spring, jaws formed upon said fingers, whereby said jaws will be supported at opposite ends with respect to each other, thereby allowing a jar to be 50 gripped and held evenly, since the strain of carrying a jar will be taken up by the end portions of said fingers in alinement with each other and adjacent the central side portions of the jar.

In testimony whereof I hereunto affix my signature in presence of two witnesses.

WILLIAM G. ZIMMERMAN.
